UNITED STATES PATENT OFFICE.

BYRON R. BACON, OF EAST ORANGE, NEW JERSEY.

CLOSET-CISTERNS.

SPECIFICATION forming part of Letters Patent No. 447,534, dated March 3, 1891.

Application filed October 27, 1890. Serial No. 368,491. (No model.)

To all whom it may concern:

Be it known that I, BYRON R. BACON, a citizen of the United States, residing at East Orange, in the county of Essex and State of New Jersey, have invented an Improvement 5 in Water-Closet Cisterns, of which the following is a specification.

Water-closet cisterns have heretofore been made with a siphon, which in some instances 10 has been stationary, and in other instances it has been connected with a moving valve, the siphon serving to draw the contents of the cistern into the flushing-pipe until the water passes below the end of the siphon. In these 15 cases, however, the valve after it has been raised by the action of the pull descends by gravity upon the seat.

In my present invention the valve is held up by a suction action produced by the descending column of water, and the valve falls 20 upon its seat after the contents of the closet have escaped through the flushing-pipe and the air has been admitted into the suction-pipe to stop the action that holds up the valve.

25 In the drawings, Figure 1 is a vertical section of the improved cistern-connection. Fig. 2 is a similar view in a modified form, and Fig. 3 is a diagram of the device with two valves in place of a double valve.

30 The flushing-pipe A passes to the closet from the bottom of the cistern B, which cistern is to be of any usual or desired character, and of a proper size to contain water for flushing the closet, and the water is to be supplied 35 to this cistern by a valve and float or ball, as usual, and at the upper end of the flushing-pipe A is a valve-seat 2, and the valve C, in its normal position, rests upon this seat 2, and there is a suction-pipe D, the long leg 3 40 of which passes below the seat 2, and the short leg 4 is formed at its lower end with a valve-seat 5, and there is any suitable lifting device to act upon the valve.

In Fig. 1 the lifting device is represented as 45 rods 6 to the cross-heads 7, upon which the pull-lever acts, a portion of the pull-lever being shown at E, and in Fig. 2 the rod 6 is represented as connected directly to the pull-lever without any cross-head, and in this Fig. 50 2 the valve C is represented as pivoted at 8, and the suction-pipe D as bent with the seat

5 at an inclination, so that the valve C will rest properly against either the seat 2 or the seat 5. In Fig. 1 the short leg of the suction-pipe is represented as a larger tube surrounding the longer leg 3, and the seat 5 is parallel 55 to the seat 2.

In both forms of my apparatus the water passes from the cistern directly through the flushing-pipe A as soon as the valve C is 60 raised, and when this valve is raised its upper face rests against the seat 5, and it is preferable to cover both faces of the valve with leather or similar flexible material, and the rush of water down the flushing-pipe A produces a powerful suction in the pipe D. Hence the valve C is held firmly against the seat 5 by atmospheric pressure, and it cannot descend upon the seat 2 as long as the water is rushing away from the cistern; but as soon 70 as the water passes out of the cistern and the atmosphere passes into the pipe D the pressure is equalized and the valve relieved from the minus pressure or suction action, and such valve falls upon the seat 2, closing the 75 outlet of the cistern, so that the cistern fills with water, as usual.

When the apparatus is constructed in the form shown in Fig. 1, the valve is in the shape of a ring, and it is necessary to provide a 80 seat for the inner edge of the valve as well as the outer edge, both at the seat 2 and the seat 5. These are represented as formed by collars or tubes around the long leg 3 of the siphon. I however do not limit myself to 85 any peculiarity in the construction of the valve or its seat, and in Fig. 3 the valve is represented as in two parts C and C', and they are connected to the pull-lever E' at opposite sides of its fulcrum, and the suction-pipe D is 90 not bent over, but stands upright, so that the valve C' rests upon the top end thereof. In this position the valve C' is held to its seat by atmospheric pressure in consequence of the minus pressure in the pipe D, and the 95 valve C cannot close until after the atmospheric pressure is equalized by air passing into the flushing-pipe A.

I claim as my invention—

1. The combination, with the closet-cistern 100 and the flushing-pipe, of a stationary suction-pipe opening at its lower end into a flushing-

pipe, a valve and a seat for the valve at the upper end of the flushing-pipe, and a second seat for the valve at the higher end of the suction-pipe, whereby the valve is held open by the suction action while the water is running from the cistern to the closet, substantially as set forth.

2. The combination, with the water-closet cistern and flushing-pipe, of a valve, a valve-seat at the upper end of the flushing-pipe, a pivot upon which the valve is allowed to swing, and a stationary suction-pipe opening at its

lower end beneath the valve-seat and having a secondary valve-seat at the other end against which the valve closes and is held during the 15 passage of the water from the cistern by the suction action, substantially as set forth.

Signed by me this 24th day of October, 1890.

BYRON R. BACON.
